UNITED STATES PATENT OFFICE.

S. S. MEILY, OF LEBANON, PENNSYLVANIA.

IMPROVEMENT IN SHIFTING BUGGY-TOPS.

Specification forming part of Letters Patent No. **55,690**, dated June 19, 1866.

To all whom it may concern:

Be it known that I, S. S. MEILY, of Lebanon, in the county of Lebanon and State of Pennsylvania, have invented a new and useful Improvement in Shifting Buggy-Tops; and I do hereby declare that the following is a full, clear, and exact description thereof, reference being had to the accompanying drawings, making a part of this specification, in which—

Figure 1 is a top view of the rails and inner seat of a shifting top removed from the seat proper. Fig. 2 is a top view of the seat, which is adapted for receiving the shifting top. Fig. 3 shows the shifting top applied to the seat. Fig. 4 is a vertical section, showing the manner of securing the shifting top to its seat. Fig. 5 is a transverse vertical section through the seat and its top.

Similar letters of reference indicate corresponding parts in the several figures.

The object of this invention is to provide a simple and efficient means for securing a buggy-top and the rails thereof to the seat, so that when desired the top can be removed, said means consisting in having the rails firmly and permanently secured to a secondary seat, which is adapted to fit on top of the main seat, and which is provided with turn-buttons that pass through the main seat and connect the secondary and main seats firmly together, as will be hereinafter described.

To enable others skilled in the art to understand my invention, I will describe its construction and operation.

In the accompanying drawings, A represents the seat of a wagon or buggy, which is constructed with inclined back A' and inclined side pieces, A², and also with a front strip, a, having its inner edge beveled, as shown in Figs. 2 and 4. I also make two oblong slots, b b, through the seat A, and face them on the bottom side of this seat with metal plates c.

Thus constructed, the seat A is adapted for receiving a cushion and keeping the same in place when a no-top seat is required. It is also adapted for receiving upon it a board, B, which forms a secondary seat, and which has its edges beveled, so as to fit snugly within the inclined sides of the main seat A, as shown in Figs. 3, 4, and 5.

The secondary seat B has the rail C and its back permanently secured to it, as shown in Figs. 1, 3, 4, and 5, which rail is adapted for receiving the folding top in the usual manner of securing folding tops to the seat-rails. By this arrangement it will be seen that the rail C is not permanently secured to the main seat A; but that it is permanently secured to a secondary seat, which is adapted to fit upon the main seat and to be firmly secured thereon.

My invention consists in providing the secondary seat B with two flat-head turning buttons, g g, having screw-stems h h formed on them, which stems pass from the bottom upward through seat-piece B, and are tapped into fixed plates j j, as shown in Fig. 4. The stems or necks of these button-heads g g are of sufficient length to allow of their passing through the oblong slots which are through the seat A, as above described, when the buttons are turned in a direction corresponding to the length of these slots.

When the seat B is placed upon the main seat the buttons g g will project from the bottom side of the same, so that they can be turned at right angles to the length of their respective slots b b, and thus be made to firmly hold the top to the seat A. By having screw-threads cut on the stems of the turn-buttons and applying these screws to nuts or plates, as above stated, the act of turning the buttons at right angles to their slots will draw the top down firmly into its place and hold it upon the seat A, so as to prevent it from working loose by the jarring motion of the wagon.

Having thus described my invention, what I claim as new, and desire to secure by Letters Patent, is—

The application of turn-buttons g g, which are constructed with screw-stems, to the secondary seat B and main seat A, these two seats being constructed and fitted together substantially as described.

S. S. MEILY.
